UNITED STATES PATENT OFFICE.

JOHN P. KELLY, OF SACO, MAINE.

DEVICE FOR CONNECTING LOOM-HARNESSES WITH THEIR ACTUATING MECHANISM.

SPECIFICATION forming part of Letters Patent No. 293,334, dated February 12, 1884.

Application filed April 2°, 1883. (No model.)

To all whom it may concern:

Be it known that I, JOHN P. KELLY, a citizen of the United States, residing at Saco, in the county of York and State of Maine, have 5 invented certain Improvements in Devices for Connecting Loom-Harnesses with their Actuating Mechanism, of which the following is a full, clear, and exact description, reference being had to the accompanying drawings, making 10 part of this specification, in which—

Figure 1 is a perspective view of a portion of a loom-harness having my improved connecting devices applied thereto. Fig. 2 is a vertical section through the top shaft of the heddle-frame and one of the fastening-eyes.

Loom-harnesses have heretofore been connected with their actuating-straps by means of eyes screwed into the top and bottom shafts of the heddle-frames, to receive the hooks at the 15 ends of the actuating-straps. These screw-eyes have been necessarily inserted into the top and bottom shafts at different distances from their ends, in order to bring them into the proper positions to receive the hooks of their 20 actuating-straps, which occupy various positions transversely across the loom, as the pulleys over which they pass do not lie in the same vertical planes. This necessitates frequent 25 changing of the positions of the screw-eyes to suit the loom to which the harness is to be applied, which consumes much valuable time and causes expensive delays. Again, when the eyes are set at the proper distance from the ends of the shafts of the heddle-frames, which distance 30 also varies according to the position which the harness is to occupy in the loom, such harness—for instance, a back harness—must always occupy this same position, and cannot be shifted or used as a front harness or in any other position but its own without first changing the 35 position of the screw-eyes. Consequently great care must be taken in arranging the harnesses in the loom to have each one in its own proper position.

My invention has for its object to overcome 40 all of these difficulties and to enable me to connect the hooks of the actuating-straps with the shafts of the heddle-frames at points at different distances from their ends without removing 45 or changing the positions of the eyes or fastening devices applied to the said shafts, thus

enabling me to effect a material saving in time and labor, avoid expensive delays, and also to use any one of the harnesses in any desired position in the loom.

55

To this end my invention consists in a fastening-eye adapted to be used either as a means of connecting one end of a draft-bar provided with a series of notches or apertures for the reception of the hook of the actuating-strap with 60 the shaft of the heddle-frame or as a substitute for the ordinary screw-eye, said fastening having a flattened or elongated loop or eye, open at its lower end to allow the end of the bar to be sprung into place therein or to receive the 65 hook of the actuating-strap, and a straight or tapering shank adapted to be driven into the shaft of the heddle-frame until the top of the head of the shank under the eye is flush with the surface of the shaft, whereby it is prevented 70 from projecting up and interfering with the “rig-band” of the heddle-cords.

In the said drawings, A A represent the top and bottom shafts of a heddle-frame, and B the heddles stretched between the same. Into each 75 end of each of the shafts A are driven two spring fastening-eyes or connecting devices, C C. Each of these connecting devices consists of a shank, a, preferably made tapering, and a head, b, from which rises the portion 5 of the 80 spring eye or loop c, the opposite portion, 6, which does not extend down to the head b, being provided with a projection, 7, at its lower end, between which and the head b is a space or opening, d, of sufficient size to admit one 85 end of a flat metal bar, D, which can thus be sprung or snapped into the elongated eye or loop c, where it is held in place by the projection 7, as shown in Fig. 2. Each of the bars 90 D is thus held by a fastening-eye at each end in a position parallel with the shaft A and at a short distance therefrom, and can be easily removed, when desired, by pressing it so as to spring open the eyes c, when it can be drawn out through the openings d. The shank a of 95 the fastening C is driven into the shaft A at the center of its thickness until the head b is embedded in the wood, so as to lie flush with the surface of the shaft, as seen in Figs. 1 and 2, leaving it perfectly smooth and even at the center, which prevents all interference with the 100 rig-band of the heddle-cords B, and allows it

to lie in a perfectly straight line from one end of the shaft to the other, as desired. The shank *a* is preferably clinched upon the inner edge or surface of the shaft *A*, as seen in Fig. 5 2, after being driven into place, as described. A great advantage is thus gained by driving in the shank of the fastening-eye instead of screwing it in, as heretofore, as in the latter case the head *b* would project up and interfere 10 with the rig-band of the heddle-cords.

The bars *D*, which may be of any suitable length, are each provided with a series of notches or open slots, *e*, for the reception of the hook *f* of the harness-actuating strap *g*, and as 15 the positions of these straps vary to a considerable extent, which must necessarily be the case, as their pulleys are not placed opposite each other for want of space, it will be seen that these bars afford a ready and convenient means for 20 connecting a strap-hook with the harness at any desired distance from the end of its shaft, as one or another of the notches *e* is sure to lie in a proper position to receive the strap-hook.

If desired, the bars *D* may be provided with 25 apertures instead of the notches *e*; but I prefer the latter, as the hooks *f* can be more readily caught therein.

By the employment of my invention any harness can be used in any desired position in 30 the loom without reference to the position of its actuating-straps, and the trouble and expense of "matching up" harnesses—that is, arranging the screw-eyes in their proper positions on the shafts—is thus entirely avoided.

35 Hitherto when a series of harnesses are taken from a loom—for instance, three, for three-shaded work—they are tied together and laid

aside until wanted again for the same description of work, the same being done for two-shaded work, or that of other shades. Consequently it becomes necessary to keep a great number of harnesses on hand. With my invention, however, no matching up is required, and as all the harnesses are at all times in readiness for instant use, a much less number will 45 be required, and a material saving in expense and labor thus effected.

The fastening-eyes *C* may be used, if desired, without the bars *D*, in place of the ordinary screw-eyes.

What I claim as my invention, and desire to secure by Letters Patent, is—

1. The combination, with the shaft of a heddle-frame, of a fastening or connecting device, *C*, consisting of a head, *b*, an open spring eye 55 or loop, *c*, with a projection, *7*, and having a space, *d*, between said projection and the head *b*, and a shank, *a*, adapted to be driven into the shaft until the head *b* lies flush with its surface, all constructed to operate substantially as and for the purpose described.

2. The combination, with the shaft *A* of a heddle-frame, of the draft-bar *D*, provided with a series of notches or apertures, *e*, and the spring fastening-eyes *C*, constructed as described, and adapted to receive the ends of said bar and secure them to the shaft *A*, substantially as set forth.

Witness my hand this 24th day of April, A. D. 1883.

JOHN P. KELLY.

In presence of—

EDWARD P. BURNHAM,
M. A. O. BURNHAM.
